DESIGN FOR A DENTAL FLASK ATTACHMENT

Dayton Bumgardner and Alexander B. Pickands,
Chicago, Ill.

Application May 21, 1937, Serial No. 69,470

Term of patent 7 years

To all whom it may concern:

Be it known that we, Dayton Bumgardner and Alexander B. Pickands, both citizens of the United States and residents of Chicago, in the county of Cook and State of Illinois, have invented a new, original, and ornamental Design for a Dental Flask Attachment, of which the following is a specification, reference being had to the accompanying drawing, forming a part thereof, and in which:

Fig. 1 is a perspective view of the dental flask attachment showing our new design;

Fig. 2 is a side elevation of the same as seen from line 2—2 in Fig. 1; while

Fig. 3 is a bottom plan view of the same.

We claim.

The ornamental design for a dental flask attachment, as shown.

DAYTON BUMGARDNER.
